US00D895652S

(12) **United States Design Patent** (10) Patent No.: **US D895,652 S**
Langan et al. (45) Date of Patent: ** Sep. 8, 2020

(54) **DISPLAY SCREEN WITH GRAPHICAL USER INTERFACE FOR AN INFUSION DEVICE**

(71) Applicant: **CareFusion 303, Inc.**, San Diego, CA (US)

(72) Inventors: **John Langan**, San Diego, CA (US); **Kelly Daoust**, San Diego, CA (US); **Luis Shriner**, San Diego, CA (US); **Wendy Smyth**, San Diego, CA (US)

(73) Assignee: **CareFusion 303, Inc.**, San Diego, CA (US)

(**) Term: **15 Years**

(21) Appl. No.: **29/648,277**

(22) Filed: **May 18, 2018**

(51) LOC (12) Cl. **14-04**

(52) U.S. Cl.

USPC **D14/486; D14/492**

(57) **CLAIM**

The ornamental design for a display screen with graphical user interface for an infusion device, as shown and described.

DESCRIPTION

The sole FIGURE is a front view of a display screen with graphical user interface for an infusion device, showing our new design.

The outermost broken-line rectangle illustrates the perimeter of a display screen or portion thereof and forms no part of the claimed design. The remaining broken lines illustrate portions of a graphical user interface and form no part of the claimed design.

1 Claim, 1 Drawing Sheet
